UNITED STATES PATENT OFFICE.

JAMES ROSENBERG, OF CLEVELAND, OHIO.

METHOD OF FORMING STEREOTYPES.

Application filed February 5, 1923. Serial No. 616,941.

To all whom it may concern:

Be it known that I, JAMES ROSENBERG, a citizen of the United States, residing at Cleveland, in the county of Cuyahoga and State of Ohio, have invented a certain new and useful Improvement in a Method of Forming Stereotypes, of which the following is a full, clear, and exact description, reference being had to the accompanying drawings.

The present invention is concerned with the typographical arts and particularly with the art of forming stereotypes, electroplates and printing plates. Forming stereotypes and electrotypes has heretofore involved the use of processes which include various steps necessitating considerable skill and labor. In forming stereotypes, for instance, an impression is usually made upon a wet matrix by an original set-up or form comprising type, zinc etchings or electroplates, the matrix first being impressed with the form and then dried. The drying of the matrix results in various distortions of the impressions due to the shrinkage of the matrix, there being such an amount of shrinkage that the stereotypes molded therefrom require considerable finishing. In making electroplates, the original form is pressed upon a special wax or lead mat to form a case. The impressed face of the lead is then suitably treated whereby copper may be electrolytically deposited thereon and be subsequently removed in the form of a shell. This process involves the use of an extremely heavy press. When wax is used to form the case, the impressed surfaces of the wax are suitably treated to receive an electrolytic deposit. The wax is then melted away from the electrolytic deposit, and it then comprises a copper molding shell. This shell is cleaned, treated with a fluxing material or chemical and then backed with soldering foil and finally reinforced with lead or type metal by pouring the metal, when in a molten condition over the soldering foil. There are many intermediate operations before the final operation of casting the reinforcing metal on the back of the copper shell.

Wherefore, the general object of the present invention contemplates the provision of a process for forming stereotypes and electrotypes in a simplified manner by directly impressing a sheet of copper or other suitable metallic foil upon the original form, whereby the metallic shells so formed may be used in molding the stereotype and become a part of the stereotype or may be used to form so-called electrotypes, thereby eliminating the use of the electrolytic method of depositing copper on a case to form a shell. A further object of the present invention is the provision of a method and apparatus for simultaneously forming a wet matrix which may be used for casting stereotype and a metallic shell which may be either used as a molding medium in producing a so-called electrotype or which may be used as a metallic matrix.

A further object of the present invention is the provision of a method and apparatus for producing a molding form suitable for casting stereotypes having relatively hard printing surfaces or for forming electroplate shells while simultaneously forming a soldering foil therefor, whereby uniform adherence between all of the backing surfaces of the metallic form or mold to the backing-up metal may be obtained.

Other objects will be apparent from the following description of my process and of the apparatus shown in the accompanying drawings, and the essential features will be summarized in the claims.

In the drawings, Fig. 1 is a perspective view of a press supporting an original form and showing the relation of the metallic foils and matrix when being positioned on the form; Fig. 2 is an enlarged cross sectional view taken through the original form; Fig. 3 is a cross sectional view taken through an electroplate mold showing a casting in the mold; Fig. 4 is a similar view showing a stereotype casting in a mold; Fig. 5 is an enlarged cross sectional view of a portion of a so-called electrotype made by my process; Fig. 6 is a similar view of a stereotype made by my process; Fig. 7 is a cross sectional

view representing an improved apparatus for forming an electrotype or a stereotype having reinforced printing surfaces; Fig. 8 is a cross sectional view taken through a press and showing an improved means for carrying out the various steps of my process when wax or similar plastic material is used as a mat; Fig. 9 is a cross sectional view taken through a flexible stereotype made in 10 accordance with my process.

In carrying out the objects of my invention, I contemplate the use of thin sheets of solder foil and thin sheets of metal having durable characteristics such as copper and 15 aluminum foils. In setting forth the various steps of my process in producing stereotypes and so-called electrotypes in a very economical manner, I will first discuss the manner in which I obtain a wet matrix 20 which, when dried, may be used to form the usual stereotype and by the same operation obtain a copper shell from the original set-up or form without resorting to the use of an electrolytic process.

25 A convenient means for carrying out the steps in the particular manner above set forth, is illustrated in Fig. 1, wherein I show a top press member 10 rigidly mounted on columns 11 and a movable form supporting 30 press member 12 which may be brought into juxtaposition with the top member 10 by any convenient means such as a hydraulic ram 13. The usual form 14 comprising set up type, etchings etc., may be placed upon 35 the movable press member 12. A sheet of solder foil 15 may then be placed over the impression surfaces of the form. I then place a copper foil 16 in superposed relation to the soldered foil 15, the face of the 40 copper foil contacting with the solder foil having previously been treated with a suitable fluxing medium. I then back up the copper foil with a plastic medium, such as a wet paper mat 17. The member 12 may 45 then be brought into compressed relation with the top press member 10 by operation of the ram 13, thus causing the paper mat 17 to compress the solder foil and copper foil into contact with the surfaces of the 50 original form 14.

As shown in Fig. 2, the result of this compressing action is to form a stereotype matrix having a flat upper surface and an impression under molding surface, the impressions in this molding surface inversely corresponding to the printing faces of the form. The formed copper shell 16^a is firmly pressed throughout all its under surfaces into contact with all of the upper surfaces of 60 the soldering foil 15^a.

If the usual stereotype is desired, the foil 17^a may be dried and then be suitably supported in a mold such for instance, as is shown in cross section in Fig. 4. The im- 65 presioned face of the matrix is exposed to

the mold cavity and the back thereof is supported by the mold member 21 which may also clamp the edges of the mat to the mold member 18. A cast 19 may be made by pouring type metal in the gate 20 at the top of 70 the mold.

If it is desired to obtain a so-called electrotype, the formed copper shell 16^a may be placed in the mold (see Fig. 3) with the soldering foil 15^a disposed toward the mold 75 cavity; the pouring of type metal 22 through the gate 23 will thus cause the type metal to become soldered to the copper shell. I thus obtain a wet matrix mold and a copper mold whereby a stereotype casting and a so-called electrotype may be obtained from 80 one impression set up. I have found that by first impressing the paper mat 17 upon the form, then separating the form from the mold and subsequently positioning the solder and copper sheets between the matrix and by again bringing the press members together, without disturbing the alignment of the first matrix impression with the set up, a more clearly defined molding 85 surface is obtained on the matrix and the drawing action of the foils in conforming to the irregularities of the original form is much more satisfactory than when the three elements, namely, the soldering foil, copper 90 foil and matrix are superposed upon a form in one pressing operation. The shell may be used only as a matrix by omitting the use of the solder foil.

In Figs. 5 and 6, I show enlarged sections through an electrotype and a stereotype which are produced by the foregoing described process. It may be noted that while the printing surfaces of the stereotype and electrotype are substantially identical as to dimensions, these printing surfaces will be slightly increased over the corresponding surfaces of the original form. This is due to the slight variations caused by interposing the thin foils between the printing surfaces of the original form which are transferred to the matrix through two thicknesses of foil. I find, however, that this variation is slight and does not interfere 100 with the efficient application of my process in the making of electrotype and stereotype in the manner described. If a standard type face is desired, however, a set of original type having printing surfaces which are less than standard may be used in obtaining 105 shells having standard printing surfaces.

The idea of forming a shell directly from the original form without resorting to the use of an electrolytic process opens up many possibilities by way of simplifying the complete process of forming stereotype with relatively hard printing surfaces, as well as forming electroplates. As an instance of this, if it is desired to obtain a stereotype 110 with the printing surfaces thereof coated 115

with a comparatively hard material, such as was heretofore obtained by electrolytically depositing nickel, steel and other hard metals on the printing surface of the cast electrotype, such a stereotype may be readily obtained by my process. A metal shell, such as I have described as being useful in forming electroplates may be placed in the stereotype mold as a substitute for the paper matrix with the solder foil exposed to the mold cavity. The stereotype whether arcuate or otherwise may then be obtained by pouring the type metal into the mold and the uniting the copper shell to the metal is immediately effected without any ancillary steps or operations.

Important advantages of this method are that a stereotype plate having a hardened printing surface may be obtained by the same operations which produce the matrix, which in this case is a metallic shell, and the usual metal casting operations.

An additional advantage is that the shell when once formed from the original may be immediately placed in the mold, thereby eliminating the time consuming operation of drying the wet paper matrix, as well as eliminating the irregularities due to the shrinking of such a paper matrix when being dried.

If it is desired to take impressions from half tones, zinc etchings, etc., an apparatus such as I illustrate in Fig. 8 may be used. This apparatus is adaptable to my process when I use wax or other plastic material as a cushioning means. The usual case forming wax such as resinol mineral composition may be used in place of a wet mat. As shown in Fig. 8, a metallic foil 25 is placed upon a form 26, there being a solder foil 25^a interposed therebetween. The form 26 may be supported upon a press member 27. The press member 27 is provided with side walls 28 which extend upwardly above the foil and are so formed as to have a close fitting relation with side surfaces 29 of a wax or cushion carrying press member 30, the pressed member 30 in this case being movable. The cushioning means 31, preferably a sheet of the wax referred to, may be placed upon the under surface of the press member 30. When the press member 30 moves downwardly toward the press member 27, the wax 31 is pressed upon the foil and causes the foil to conform to the printing surfaces of the original set-up 26. The side walls 28 prevent the wax from flowing from between the pressed members. The top surface of the metal foil 25 may be coated with any suitable lubricant to further the flowing action of the metal and the wax as the wax is pressed upon the form and to facilitate the separating of the foil from the wax when the mold members are parted. It will thus be seen that the wax 31 need not be removed

from the pressed member 30 after each operation but may be used for subsequent shell forming operations.

If it is desired to transfer half tones to the foil, a flat surfacing member may be interposed between the two pressed members and the top member brought downwardly thereupon, whereby the impressioning surfaces of the wax may again be leveled.

My method also contemplates the production of electroplates without the use of a casting process. In Fig. 7, I show an apparatus whereby I fulfill the steps in such a process. In this case the paper matrix may be used as a cushioning means or any plastic material may be used as a mat which has a melting point higher than that of lead or type metal. The mat, solder foil and flux treated copper foil may be superposed in a press such as illustrated in Fig. 1 and in the manner described and an impression may then be taken of the original set-up or form. The three elements may then be removed from the press without disturbing their superposed relation and placed in a roller press.

A roller press suitable for the above purpose may comprise a flat bed or support 34 and a metal melting roll 35. A plate of lead or type metal 36 may be superposed upon the impressioned shell in contact with the solder foil; the thickness of the plate 36 combined with the matrix and foil being greater than the clearance space between the supporting bed 34 and the roller 35. The roller 35 is provided with any suitable heating means such as electrical elements 38 whereby the temperature of the roller may be maintained greater than that of the melting point of the plate of metal 36. It will be seen that movement of the bed 34 will cause the roller 35 to have a compressing action upon the plate 36, as well as a melting action thereon. The metal plate will be melted and the under surface thereof caused to conform to the irregular surfaces of the shell and become united therewith. The matrix may then be removed from the plate and a so-called electrotype is thus obtained.

I have also found that it is practical to position the formed shell upon a spring metal back by the use of a suitable flexible cement which will fill all of the irregular spaces between the backing metal and the under surface of the shell. In Fig. 9, I show a spring metal back 40 upon which a shell 41 is maintained by a hard cement 42. The cement serves to fill all of the spaces and support the elevated printing surfaces of the shell while permitting the backing plate to be sufficiently flexible to conform to a printing roll.

From the foregoing description, it may be readily understood that my process of forming "electrotype" and stereotype has a number

of advantages in that I eliminate many operations which have been heretofore thought necessary. In producing the latter, for instance, the difficulty of overcoming variations due to shrinkage of a wet paper matrix are eliminated by the present process. Furthermore, it is possible to readily obtain a hard surfaced stereotype without resorting to the expensive operation of depositing 5 aluminum, steel, nickel or other metal upon the cast type electrolytically. In producing electrolyte by my process, I eliminate the exacting and tedious operations of case making which involves the steps of shaving, 10 graphiting, black leading, electrical deposition of metal, melting wax from electrolytically formed shell, cleaning the shell, etc. Furthermore, my process is readily adaptable to the use of zinc foil and aluminum foil, as well as copper foil, and likewise, 15 the step of forming the shell from the foil, simultaneously forms the solder foil in a more perfect manner than has heretofore been practical. It will be readily understood 20 that white face printing may also be obtained by producing my shells from reverse original forms.

I claim:

1. The method of producing printing 30 plates which includes the step of forming metal shells by backing a sheet of metallic foil and a superposed sheet of solder foil with a cushioning means and pressing the foil into intimate contact with the surfaces 35 of an original form.

2. The method of producing printing plates which includes the step of forming metal shells by backing a sheet of metallic foil and a superposed sheet of solder foil with a wet 40 mat and pressing the foil into intimate contact with the surfaces of an original form whereby a metallic shell and a wet molding matrix are formed.

3. The method of producing printing plates 45 which includes the step of forming copper shells by backing a sheet of thin copper in a thin sheet of solder foil with a paper mat and pressing the thin copper into intimate 50 contact with the surfaces of an original form.

4. The method of producing printing plates which includes the step of making up an original form, placing a sheet of solder foil over the form, treating a thin metallic 55 sheet with a fluxing solution, placing said treated sheet in superposed relation to the solder foil with the flux treated surface thereof in contact with the solder foil, placing a cushioning means over the metallic 60 sheet, and pressing said solder foil and metallic foil into intimate contact with the printing surfaces of the original form.

5. The method of producing printing plates 65 which includes the step of making up an original form, treating the printing sur-

faces thereof with a lubricant, placing a sheet of solder foil over the form, treating a thin metallic sheet with a fluxing solution, placing said sheet in superposed relation to the solder foil with the flux treated surface 70 thereof in contact with the solder foil, placing a plastic medium over the metallic sheet, and pressing said solder foil and metallic sheet into intimate contact with the printing surfaces of the original form. 75

6. The method of forming printing plates which includes the step of placing an original form upon a press member, placing a solder foil over the form, treating a relatively thin metallic foil with a metal fluxing 80 medium, superposing said metallic foil over the solder foil with the flux treated surface thereof in contact with the solder foil, placing a cushioning means over the back of the metallic foil, and exerting pressure upon the cushioning means whereby the solder foil and copper foil are caused to conform to the irregular printing surfaces of the original form. 85

7. The method of forming printing plates 90 which includes the step of placing an original form upon a press member, positioning a solder foil over the form, treating a relatively thin metallic sheet with a fluxing medium, superposing said metallic sheet over the solder foil with the flux treated surface 95 thereof in contact with the foil, placing a plastic heat resisting means over the back of the metallic foil, exerting pressure upon the plastic means whereby the solder foil and copper foil are caused to conform to the irregular printing surfaces of the original form; removing the mass from the press, placing a sheet of low melting point metal 100 in contact with the solder side of the mass and applying pressure and heat to said metal and applying pressure and heat to said metal to unite it to the formed metallic sheet. 105

8. The process of forming printing plates comprising placing a metallic foil over an original form, backing said metallic form with plastic material, compressing said foil and plastic material on the printing surfaces of the original form, whereby the foil is caused to conform to the irregular printing surfaces of the original, removing the 110 pressed mass from the formed foil, placing a sheet of low melting point metal in contact with the formed foil and applying pressure and heat thereto to cause said last named metal to unite with the formed foil. 115

9. The process of forming printing plates comprising placing an original form in a press, superposing a relatively thin metallic foil over the printing surfaces of the original, backing said foil with a plastic material, compressing the plastic material, the foil and the original whereby the foil is caused to conform to the printing surfaces of the original, and backing the side of the shell thus formed, which was in contact with 120 125 130

- the printing surfaces of the original, with metal.
10. The process of forming printing plates comprising placing an original form in a press, superposing a relatively thin metallic foil over the printing surfaces of the original, backing said foil with a heat resisting plastic material, compressing said material, foil and original whereby the foil is caused to conform to the printing surfaces of the original, and backing the side of the shell thus formed which was in contact with the printing surfaces of the original with a low melting point metal by applying heat and pressure to said metal when in the form of a sheet superposed upon the foil.
11. The process of forming printing plates which includes the step of making up an original, comprising printer's type, electroplate, zinc etchings and the like, placing said form in a press, superposing a thin sheet of solder foil over the printing surfaces of the original, treating one side of a relatively thin sheet of copper foil with a solder fluxing solution, placing the copper sheet with the treated surface thereof in contact with the solder foil, backing said copper foil with a heat resisting plastic mat, compressing said solder foil, copper foil and mat to cause the solder foil and copper foil to conform to the irregular printing surfaces of the form, releasing pressure on the three elements thus formed, reversing the elements while maintaining their superposed relation, placing a plate comprising a low melting point metal in contact with the solder foil and applying pressure and heat to said plate to cause the plate to melt and unite with said formed copper foil.
12. The process of forming printing plates which includes the step of making up an original printing form, placing said form in a press, superposing a thin sheet of solder foil over the printing surfaces of the original, treating one side of a thin sheet of copper foil with a solder fluxing solution, placing the copper sheet with the treated surface thereof in contact with the solder foil, backing said copper foil with a heat resisting plastic mat, compressing said solder foil, copper foil and mat to cause the solder foil and copper foil to conform to the irregular printing surfaces of the form, removing the compressed elements, placing a sheet of metal in contact with the solder foil and applying heat and pressure to said last named sheet of metal while supporting said formed copper foil upon the mat.
13. In a process of the character described, the steps which include the positioning of a thin metallic foil over the printing surfaces of an original form, compressing said foil into intimate contact with the original whereby the entire upper surfaces and lower surfaces of the foil are caused to conform to the irregularities of the printing surfaces of the original, and backing the side of the metal shell thus formed which was adjacent the original, with other metal.
14. In a process of the character described, the steps which include the positioning of a thin web of metal over the printing surfaces of an original form, compressing said web into intimate contact with the original whereby the upper surface of the web is formed into a replica of the printing surfaces of the original, and backing the lower side of the shell thus formed with other metal.
15. In a process of the character described, the steps which include the positioning of a metal web comprising a sheet of metal having a melting point higher than type metal and a sheet of solder foil over the printing surfaces of an original form, compressing said web into intimate contact with the original whereby a replica of the original form is produced on the upper side of the web and removing said formed web.
16. The process of forming stereotype and electrotype which comprises the making up of an original form, placing the form in a press, superposing a solder foil over the printing surfaces of the original form, treating a relatively thin metallic sheet with a solder flux, positioning said sheet with the treated surface thereof in contact with the solder foil, placing a plastic material over the metallic sheet, pressing the plastic material, the sheet and the foil upon the original, whereby the foil and sheet will conform to the printing irregularities of the original form, removing the plastic material, the foil and sheet from the press without disturbing their superposed relation, placing a sheet of low melting point metal in contact with the solder side of the shell thus formed and applying heat and pressure to the last named metallic plate while supporting the shell with said plastic material whereby the surface of the plate contacting with the shell will conform to the irregularities thereof and be united thereto by said solder.
17. The process of forming stereotype and electrotype which comprises the making up of an original form, placing the form in a press, treating one side of a solder foil with a lubricant, superposing the solder foil over the printing surfaces of the original form, with the lubricated surface of the foil contacting with the original, treating a relatively thin metallic sheet with a solder flux, positioning said sheet with the treated surface thereof in contact with the solder foil, placing a heat resisting plastic material over the metallic sheet, pressing the plastic material, the sheet and the foil upon the original, whereby a replica of the original is formed on the upper surfaces of the sheet and the

foil and an inverted replica is formed in the mat, removing the plastic material, the foil and sheet from the press without disturbing the superposed relation thereof, 5 placing a sheet of low melting point metal in contact with the solder side of the shell thus formed and applying heat and pressure to the last named metallic plate while sup-

porting the shell by said plastic material whereby a surface of the plate contacting with the shell will conform to the irregularities thereof and be united thereto by said solder. 10

In testimony whereof, I hereunto affix my signature.

JAMES ROSENBERG.
